TAP TUBE

Herman H. Harr, Cleveland, Ohio

Application August 1, 1940, Serial No. 342,373

2 Claims. (Cl. 225—3)

This invention relates to improvements in tap tubes, that is to say apparatus for drawing beverages containing activating gases, such as beer, from containers that are subjected to internal pressure.

One of the objects of the invention is the provision of apparatus for the purpose stated wherein the beverage is conducted through a small bore tube from the bottom of the container therefor and in which means are provided near the faucet for throttling the flow through said tube in order that the rate of discharge from the faucet may be regulated or "tuned" to provide just the right amount of foam.

Another object of the invention is to provide vent means contained in the tap tube assembly.

A further object is the provision of means for cooling the exposed part of the tap tube.

Still another object is the provision of convenient means for removably mounting the tap tube in the upper wall of a cabinet.

Other objects and features of novelty will appear as I proceed with the description of those embodiments of the invention which, for the purposes of the present application, I have illustrated in the accompanying drawing, in which

Fig. 1 is a view principally in vertical central section of apparatus embodying the invention.

Fig. 2 is a horizontal sectional view taken substantially on the line 2—2 of Fig. 1, and

Fig. 3 is a fragmental elevational view of another form of the invention.

In the drawing 16 represents the upper wall of a cabinet from which may be dispensed beer or other beverage of the type that contains activating gases. Within the cabinet there may be a barrel, keg or other container, the upper end wall of which is indicated at 9. Customarily carbon dioxide or air under pressure is injected into the container above the liquid level therein, which has the double function of preventing the activating gases from leaving the liquid and supplying pressure to lift the beverage through the tap tube to the faucet. It is to be understood that in some instances the container may be a barrel or keg in which the beverage is supplied, while in other instances the beverage may be piped from such barrel or keg into a container supplied with the cabinet. Furthermore in some installations the tap tube may extend through the cabinet into a barrel or keg supported therebeneath.

Cabinet 10 is provided with an opening 11 through which the tap tube is inserted. The lower end of the latter projects down to the bottom of the container, while its upper end extends

above the container, and the cabinet in which the container is enclosed, upwardly far enough to bring the faucet to a convenient level.

The tap tube itself comprises a pipe 12 of sufficiently heavy gauge to be quite rigid. At its upper end this pipe carries a plug 13 which is threaded in place and has an annular shoulder 14 for a purpose later to appear. Another plug 15 is threaded into the lower end of the pipe and projects downwardly therefrom. Both of these plugs are drilled out centrally to receive a small tube 16 which may have a comparatively thin wall and possess little rigidity since it is protected by the pipe 12.

A cap 17 of the same diameter as the pipe is threaded onto the projecting end of plug 15 and has perforations 18 near its lower end to provide a free passage for liquid. This cap encloses a strainer 19 which is slipped over and frictionally engages the lower protruding end of tube 16. Any particles of pitch or other foreign matter are thereby excluded from the tube 16. When the apparatus is to be cleansed it is of course a simple matter to unthread cap 17, after which strainer 19 may be removed and cleaned. It will be noted that the pipe 12 together with the plugs 13 and 15 provide a dead air pocket surrounding the major portion of the length of tube 16, thereby effectively insulating that tube.

The upper end of pipe 12 is attached to a head 20 consisting of a block of solid metal with two intersecting passages 21 and 22 therein. On the lower side of this block concentric with passage 22 there is an externally threaded projection 23 which receives the threaded part of a coupling 24 with a lower portion of constricted diameter which engages shoulder 14 of plug 13. A gasket 25 is interposed between the head 20 and plug 13. Tube 16 projects into passage 22. When the coupling 24 is threaded up tightly gasket 25 seals the joint.

In the upper side of head 20 there is a plug 26, threaded internally and externally, which sets into a threaded socket in the head above a gasket 27. The internal threaded opening of this plug receives the threaded portion of a stem 28, the upper end of which is fitted with a knob 29 and the lower end of which consists of a smooth walled peg 30 that extends into passage 22. This peg constitutes a throttle valve which regulates the size of the connection between passages 21 and 22 and thereby regulates the rate of flow of liquid into passage 21 and hence into the faucet.

The faucet 31 is attached to head 20 by suitable means which may embody a hollow con-

nection 32 threaded into the head and registering with passage 21, together with a coupling sleeve 33 which binds the faucet proper to plug 32. The faucet valve is of the type disclosed in my Patent 2,170,922. A valve piece 34 is adapted to engage a seat 35 to shut off flow. This valve piece is on the inner end of a stem 36 which has an enlarged cylindrical portion 37 that is slidably supported in a guiding socket 38 of the faucet. This portion 37 has a slot 39 intermediate its ends which receives a bar 40 on the lower end of a handle 41 which is mounted for rocking movement in the faucet body. 42 is a small threaded plug with a vertical slot 43 in one side and a gasket 44 underneath its head. When the plug is threaded upwardly somewhat so as to expose slot 43, air can enter and mix with the beverage to provide whatever degree of aeration may be desired. There is also a small port 45 with which a slot 46 in the stem registers when the valve is closed. This latter arrangement prevents the formation of a partial vacuum and slow drip from the closed faucet in the event that plug 42 is screwed down.

In order to provide further cooling and insulating means for the exposed part of the tap tube, I surround the latter with a cylindrical casing 47 which may be formed of a plastic or other non-metallic material. This casing fits into an annular recess in head 20 so as to be flush with the side wall of the head, and at its lower end it fits into an annular plate 48 which is threaded upon a collar 49 that is shrunk onto the pipe 12. A set screw 50 prevents accidental unthreading of the plate.

Casing 47 is received in a sleeve 51 of metal which acts as a support for the casing and tap tube, being provided with a collar 52 which is shrunk onto the sleeve and serves to engage the upper surface of the cabinet. The sleeve 51 fits snugly within the opening 11 of the cabinet. This supporting sleeve member is threaded on its lower extremity to take a flanged cap 53 which acts with the collar 52 to clamp the sleeve to the cabinet. In order to provide a shoulder against which the plate 48 may rest, an internal bead 54 is rolled into the sleeve. There are openings 55 in the plate 48 and openings 58 in cap 53. The annular space within cylindrical casing 47 is therefore in free communication with the interior of the cabinet 10 which is usually refrigerated, and the cool air in the cabinet circulates through this annular space and serves to maintain cool the tap tube including the contents of small tube 16.

I also provide in the assembly a convenient means for venting the container. For this purpose I employ a tube 60 of small size having its lower end turned at right angles and extending through a hole in the pipe 12 at a point just below the upper wall of the container. The joint is soldered or otherwise made tight. The upper end of this tube is also turned at right angles and is set into and sealed within a small plug 61 that is threadably mounted in pipe 12 near the upper end of the latter. Plug 61 also receives the threaded inner end of a vent tube 62, the bore of which registers with the bore of tube 60. Tube 62 projects through cylindrical casing 47 and carries a tire valve in its extremity. A cap 63 with a center post 64 is adapted when threaded upwardly to open the tire valve, permitting gas to escape and thereby lowering the pressure in the container.

In cases where container 9 is not a barrel or keg but is a special container to which the beverage is piped, it is necessary for the operator in filling the container to open the valve in pipe 62 in order to exhaust the air above the entering beverage and permit the beverage to rise to the desired height in the container.

Suitable means are provided for sealing the pipe 12 into the opening in the top of container 9. As illustrated herein the container may include a hollow plug 65 threadably mounted in the opening in the container and externally threaded to take a packing gland 66 containing a packing 67 which may be compressed to tightly grip the pipe and to seal the joint between it and the container.

As a means for cooling the head 20 at the upper end of the tap tube I may provide a small tubular conductor 70 within casing 47, having at its upper end a plug 71 with an extremely fine drilled passage therethrough acting as a nozzle through which cold water may be sprayed against the base of the head. This spray is so fine that it produces a mist within the casing, and the consumption of water is very light. The conductor 70 may be connected with any convenient source of cold water. It is caused to project through one of the openings 58 in cap 53 and upwardly through one of the openings 56 in plate 48. It may be supported by any suitable means either from that plate or from cap 53.

It is not always desirable or convenient to use a container of any kind in the cabinet. In some cases the keg or other container may be located below the floor of the room in which the cabinet is positioned. An arrangement for this purpose is illustrated in Fig. 3. Here the pipe 12 is of somewhat reduced length and is suitably connected below the top of cabinet 10 with a tubular conductor 68 which extends down through the cabinet into any storing and cooling compartment which may be available. There it is joined by suitable connections with a tap tube 69 of conventional character, that is one with an internal diameter of five-eighths of an inch approximately, that is connected into the container 70 and sealed by suitable means indicated generally at 71. This connection includes provision for receiving through a conductor 72 carbon dioxide gas or air under pressure, which provides counterpressure to hold the activated gases in the beverage and pressure to lift the beverage through the tube 69, conductor 68 and the tap tube 12 of my invention up to the faucet, not shown. While in this case the quantity of beverage standing at any given time in the connections between the container and the faucet is greater than in my preferred form of the invention illustrated in Fig. 1, still it is much less than where the beverage is conducted through a coil of pipe in a cooling vessel or receptacle which has been commonly done heretofore.

The tube 16 is preferably of an outer diameter of one-quarter inch, and a bore of approximately three-sixteenths of an inch. Consequently the entire volumetric capacity of the tube in the usual installation is no more than a few cubic inches. Even this small amount of beverage however is maintained at substantially the desired temperature for considerable periods owing to the insulation provided by the space within pipe 12 and the circulation of cooling air within the cylindrical casing 47.

When the faucet is opened beverage flows up-

wardly through the tube 16 with very little agitation. The pressure on the liquid at the top of tube 16 or in the head 20 is greatly reduced from that in the container itself largely, I believe, because of the friction presented by the walls of the tube, the small bore of the tube causing this friction to be effective against substantially all of the liquid flowing through the tube. Additionally, the throttle valve 30 serves to regulate the flow within fine limits, and since the knob 29 is within easy reach of the operator while drawing beverage he may readily "tune" the flow to give best results.

Having thus described my invention, I claim:

1. In dispensing apparatus for drawing beverages containing activating gases from a container, a cabinet, a draft pipe adapted to be mounted in the container with one end projecting therefrom, an inner tube mounted in said pipe, said tube being of less external diameter than the internal diameter of said pipe, a head in which the upper end of said pipe is mounted, a faucet carried by said head, said head having a passage therethrough for connecting said tube with said faucet, a cylindrical casing surrounding said pipe and extending from said head downwardly to said cabinet, and means extending upwardly from the cabinet through said casing for

producing a fine spray of cold water within the casing beneath said head.

2. In dispensing apparatus for drawing beverages from containers replaceably mounted in a cabinet wherein a draft pipe is mounted in the container with one end projecting therefrom and a head is mounted on the projecting end of said pipe carrying a dispensing faucet communicating with said pipe, the combination of a cylindrical casing surrounding said pipe and extending from said head downwardly to said cabinet, a cylindrical sleeve adapted to snugly receive the lower end of said casing, there being an opening through said top cabinet wall through which said sleeve passes, a collar fixed on the outer wall of said sleeve and engaging the upper surface of said cabinet wall, a securing member attached to the lower end of said sleeve and engaging the lower surface of said cabinet wall, a deformation on the inner wall of said sleeve engaging the lower end of said casing and limiting the downward movement thereof, and said sleeve and casing interengaging sufficiently to provide the sole support for holding said head and faucet firmly in position when said casing engages said deformation.
